UNITED STATES PATENT OFFICE.

SAMUEL H. TODD, OF DETROIT, MICHIGAN.

ELECTRIC SWITCH.

Application filed March 18, 1921. Serial No. 453,484.

To all whom it may concern:

Be it known that I, SAMUEL H. TODD, a citizen of the United States, residing at Detroit, in the county of Wayne and State of Michigan (whose post-office address is 13131 Lincoln Ave.), have invented a certain new and useful Improvement in Electric Switches, of which the following is a full, clear, and exact description, reference being had to the accompanying drawings.

This invention relates to electric switches and has for its main objects the provision of a switch which can be operated by a comparatively small amount of movement of the actuating member and provide a comparatively large and quick movement of the contact member; the provision of a switch of very small external dimensions which however shall be capable of making and breaking a circuit of considerable magnitude; the provision of a simple and compact switch whose parts shall be of rugged construction; the provision of a switch operating upon a new principle; while further objects and advantages of this invention will become apparent as the description proceeds. I have devised and produced this switch primarily for use in connection with a thermostat such as often used for the control of heat and cold producing apparatus, and to the end of providing a mechanism which shall operate with a minimum spread of temperature, but my improvements are susceptible of use in many other relations in the arts.

In the drawings accompanying and forming a part of this application I have shown a preferred embodiment of my inventive idea, and in this specification I have described such embodiment with particularity but I do not thereby limit myself to the constructions and arrangements of this embodiment in any degree whatever except as specifically recited in my claims since many changes can be made within the scope of my inventive idea. In these drawings Fig. 1 is a sectional view of my improvements corresponding to the broken line 1—1 of Fig. 2 and looking in the direction of the arrows; Fig. 2 is a sectional view corresponding to the broken line 2—2 of Fig. 1 and looking in the direction of the arrows; Fig. 3 is a perspective view of one of the movable contact members; Fig. 4 is a perspective view of one of the spring hammers; Fig. 5 is a per-

spective view of one of the hammer-levers 55 and Figs. 6 and 7 are respectively side and face views of the switch-operating member.

Describing by reference characters the parts shown in this particular drawing, but without intent to limit myself thereto except as already set forth, 1—1 represents a substantially rectangular base-member of insulating material having at one end the lateral ears 2—2 whereby it may be secured to a suitable base 3 such for example as the cap of a thermostat whose movable member is indicated at 4. Formed in one face of the member 1 is a longitudinal groove 5 which terminates short of the margin of the block at the upper end as shown in Fig. 1; and formed in the opposite side of the block is the screw-threaded recess 6 adapted for the reception of the hollow cap 7, also preferably made of insulating material and having an aperture 8 for the conductor (not shown). Traversing this block at each side of the groove 5 are the conducting sleeves 9—9, having contact screws 10—10 located inside said recess and having secured to their opposite ends the fixed contact members of the switch. Each of these members comprises a base part 12 and a terminal portion 13, the latter being curved upwardly as shown in Fig. 1 and formed in two closely adjacent fingers having outturned tips 14—14 as shown in Fig. 2, each of said devices being made of resilient spring metal of an electrically-conducting nature such as spring copper.

Rigidly secured in the base of the groove 5 is a U-shaped, metallic, channel-member 16 having a forward projection 17 at the middle of each of its lips and having a projection 18 at the end of each of its lips. Between the projection 18 are secured the extension pieces 19—19 to the sides of which are secured the supporting plates 20—20, the members 19—19 being spaced from the bottom of the member 16 as shown at 21—21. The movable contact-member comprises two U-shaped pieces rigidly connected together base to base, one of said pieces having arms 24—24 which embrace the projections 17—17 and are pivoted thereto on fixed rivets 25—25; and the other of said pieces having arms 26—26 adapted to enter the spaces between the lips 14—14 of the contact fingers and close the circuit therethrough. The com-

mon base of these members is indicated at 27. At each side of the pivot 25 the tip of the projection 17 is bent outwardly as shown at 28 to provide stops limiting the movement of the contact member.

The actuating devices for moving this contact member are carried by the plates 20-20 and consist of two opposed hammers one of which is illustrated in perspective in Fig. 4. The body of each of these hammers is made of a single apertured piece of sheet metal bent to produce two parallel sides 30-30 connected by the integral web 31, the lines of bending traversing said aperture so that the latter produces a deep notch 32 which separates the web into two spaced portions. One extremity of each of these devices is pivoted between the plates 20-20 by means of the pins 33-33, their notches 32-32 facing each other and the webs 31 at their free ends constituting striking portions so located relatively to the movable switch member as to contact with the portion 27. These hammer members are drawn yieldingly towards each other by means of a spiral spring 35, their approaching movement being limited by suitable pins 36 carried by the plates 20-20. Pivotaly mounted upon a transverse pivot 40 carried at the free-end of each of the hammer-members is a dog 41 having an angularly projecting tail 42 yieldingly held against a stop-pin 43 by means of a suitable spring 44 carried by the hammer.

Slidably mounted inside the channel-member 16 is the operating member of the switch, which consists of a U shaped metal bar 45 whose lower end is here shown as connected to the member 4 symbolizing any kind of actuating device whatsoever. At its middle portion the sides of this bar are extended as shown at 46 in Figs. 6 and 7, producing a pair of apertured ears 47 and at each side thereof a deep notch 48. Pivoted inside the walls of the member 16 opposite each of the hammer members is a lever shown in Fig. 5, comprising spaced side-members 50-50 and a connecting web 51 adjacent to its free end, each of said levers being traversed by a rivet 52 which fits in one of the notches 48. The member 45 therefore projects between the two side members of each lever and is here shown as guided by the rivets 53 which support those levers. The ears 47 are connected by a rivet 54 which receives the slotted end of the fork 55 whose handle 56 projects loosely through a hole 57 in the base of the movable contact member, this handle being surrounded by a spring 58. As a consequence of this construction, reciprocation of the member 45 causes the rivet 54 to pass by the rivet 25, and also causes the levers 50-50 to describe the arcs *a-a* shown in Fig. 1.

The operation of the switch is as follows:

Starting with the parts in the position shown in Fig. 1, a downward motion of the member 45, whether produced by the member 4 or otherwise, will cause the lowermost lever 50 to swing downwardly. Inasmuch as its arc intersects the end of the dog 41, the dog and its attached hammer are caused to accompany this movement, thereby displacing the striking portion of the hammer away from the movable switch member with which it was previously in contact, and exerting tension on the spring 35. Meanwhile the other lever 50 comes in contact with the corresponding dog, but the yielding nature of the same when approached from this side permits the lever to pass freely by without displacing the upper hammer. Owing to the fact that the arcs defined by the levers and hammers rapidly diverge, the time soon comes when the lowermost dog escapes past the end of its lever whereupon the lower hammer, impelled by the spring 35, strikes the switch member 26 a sharp blow driving it out of engagement with the contact fingers 14; and inasmuch as the pivot 54 has meanwhile been moved past the pivot 25, which constitutes the dead center of the spring 58, the action of said spring is to hold such member in the position shown in phantom at *b* to which it was thrown by the hammer. In this way a very sharp and quick breaking of the circuit is effected; besides the inertia of the contact member, coupled with the tension of the spring 58 causes that member not only to rest against the opposite hammer but even to displace that hammer a little way, thus leaving the contact member always in position for reverse movement. It is idle to speculate whether it is the hammer or the spring which produces the operation. The hammer at least starts the movement and is essential to the device; the spring may perhaps complete the movement and helps hold the parts in place for the next operation, but is not indispensable if the inertia of the hammer is properly chosen and if suitable means are employed to hold the parts in place.

If it now be desired to close the switch, either thermostatically or otherwise, an upward movement of the member 45 produces identically the same operations as before excepting in reverse order with the result that the movable member is again driven into place between the contact fingers 14 exactly as shown in Fig. 1. This switch offers special advantages in connection with a thermostat owing to the fact that actuation can be produced by a comparatively small amount of force and with a very small movement of the member 45. The rapidity of movement of the levers 50-50 can be varied if desired by changing the distance between the pivots 52 and 53, and the point of

divergence of the arcs defined by the levers and their corresponding hammers can be varied by changing the relative positions of the pivots 33 and 53.

- 5 The rapidity with which the hammers are displaced by the levers and the time of their slipping past those levers is determined by the angle of the arcs. The hammers drive the contact member in the same direction as
 10 the bending of said spring but with this advantage that the hammers initiate the movement of the contact member at an accurately determinable time which is earlier than would be produced by the spring alone and
 15 requires a smaller amount of movement of the operating member.

The entire switch mechanism can, if desired, be grounded, or it can very easily be insulated merely by inserting a strip of
 20 mica between the two bases of the members 24 and 26, and making the handle 56 of the yoke of non-conducting material. All the parts of the switch are simple, are few in number, and can be made from sheet metal
 25 by simple process. However I do not restrict myself to any of the constructions, arrangements, relations or designs described or illustrated herein except as the same are specifically recited in the annexed claims.

30 Having thus described my invention what I claim is:

1. In an electric switch, in combination, a pair of contact members, one of which is movable, a pair of opposed hammer-members arranged facing each other upon opposite sides of said movable member, and means including a spring for producing a quick blow of either of said hammer-members against said movable contact member
 40 for moving it into or out of engagement with the other contact member.

2. In an electric switch, in combination, a pair of contact members, one of which is movable, a pair of opposed hammer-members arranged facing each other upon opposite sides of said movable member, means for producing a quick blow of either of said hammer members against said movable contact member for moving it into or out of engagement with the fixed contact member, and means for holding said movable member into which ever extreme of its movement it is impelled by said hammer members.

3. In an electric switch, the combination with a pair of spaced pivoted hammers, of a movable contact member located between them and adapted to be struck by the hammer nearest thereto, means movably maintaining said contact member in contact with one or the other of said hammers, and means for operating that hammer for driving said member to the other hammer.

4. In an electric switch, in combination, a movable contact member pivoted to swing between limits, spring means normally hold-

ing said member at one or the other of such limits, a pair of hammers located one at each of such limits and adapted to be engaged by said member, and means for first retracting that hammer which momentarily is engaged by said member and then impelling it violently against said member, whereby said member is driven toward the other hammer.

5. In an electric switch, in combination, a movable contact member, an operating member, a pivoted hammer, and operative connections between said operating member and hammer adapted upon reciprocation of the former to actuate the latter to strike violently against said movable contact member in the line of direction of its movement, said connections including a dog carried by the hammer in position for engagement by the operating member.

6. In an electric switch, in combination, a movable contact member, a pair of hammers located on opposite sides thereof, a reciprocable operating member, and means operatively connecting said operating member with each of said hammers whereby upon movement of the former one or the other of said hammers will be caused to strike the movable contact member and move the same in a direction determined by the direction of movement of said operating member.

7. In an electric switch, in combination, a movable contact member, a pair of hammers located on opposite sides thereof, a reciprocable operating member, a dead-center spring operatively connecting said members, and means actuated by the same movement of said operating member which causes a movement producing tendency on the part of said spring for causing the corresponding hammer to strike said contact member and drive it in the same direction as indicated by said spring.

8. In an electric switch, in combination, a pivoted contact member, a pair of hammers located one at each limit of swinging movement of said contact member, a reciprocable operating member movable past such pivot, a dead center spring connected between said members and movable past such pivot, and means connected to said operating member and engaging said hammers alternately to actuate them to drive said contact member in the direction indicated by said spring.

9. In an electric switch, in combination, a support, a contact member pivoted thereto, a pair of levers pivoted to said support, one at each side of said contact member, a second support, and a pair of hammers pivoted thereto, one opposite each lever, and adapted to strike said contact member, the arc of movement of each lever intersecting the arc of movement of the corresponding hammer, an operating member adapted to swing said levers to displace one or the other of

said hammers, and spring means for thereafter returning said hammer with a blow which displaces said contact member.

10. In an electric switch, in combination, 5 a pair of pivoted hammers, a lever pivoted opposite each hammer, the arc of movement of each lever intersecting that of the corresponding hammer, spring means tending to move said hammers toward each other, a 10 movable contact member located between said hammers, and an operating member for said levers adapted to swing the same in a direction to displace one of said hammers until it reaches the point of intersection of 15 such arcs and then to allow said hammers to strike said contact member in movement producing relation.

11. In an electric switch, the combination with a pivoted movable contact member of 20 a dead-center spring, means for moving the spring past the pivot of said member, and hammer mechanism released at a predeter-

mined time compared with the movement of said spring for initiating the movement of said contact member which said spring tends 25 to produce.

12. In automatic controlling mechanism, the combination with a reciprocable member of an electric switch comprising a reciprocable operating member, a pivoted contact 30 member, a spring connected thereto and movable by said operating member to opposite sides of the pivot axis, and spring hammers actuated by the same movement of said operating member to strike said contact 35 member as soon as said spring has reached a predetermined position relative to said pivot axis for initiating movement of said contact member in the direction sought to be produced by said spring. 40

In testimony whereof, I hereunto affix my signature.

SAMUEL H. TODD.
